RADIO TRANSMITTER CONTROL

Paul E. Fischler, Buffalo, and Paul John Thut,
East Rochester, N. Y., assignors to Technical
Alliance, Inc., a corporation

Application June 28, 1949, Serial No. 101,844

6 Claims. (Cl. 250—17)

1

This invention relates to a radio transmitter control and more particularly to a radio transmitter of the type commonly called a pull-box, for use where it is desired to transmit a series of audio impulses.

Such devices are particularly well adapted for use in connection with fire alarm systems of the type described in the copending application, Serial Number 30,923, filed June 3, 1948, but may be used for other purposes.

An object of the invention is to provide a transmitter of the type described of compact construction, so that it may be readily mounted in the usual pull-box commonly employed with fire alarm systems and the like, the transmitter being entirely self contained, including the power supply.

Another object is to provide a radio transmitter enclosed in a casing having a main door which may be locked and an auxiliary door which may be opened by the public in order to operate the release lever to actuate the mechanism in the casing to automatically send in the alarm.

Another object is to provide a device of the character described having a motor driven timer unit adapted to first connect the power supply to the transmitter and allow sufficient time for the tubes in the transmitter to warm up, and then release the pulsing mechanism which pulses the carrier wave, thereby indicating which box is sending in the signal to the centrally located receiver from which the alarm may be broadcast.

A further object is to provide a simple motor driven timer having few parts and which may be removed from the box as a unit.

Other objects and advantages will be apparent from the following specification where, for example, is shown a preferred embodiment of the invention suitable for use with the fire alarm systems disclosed in the aforesaid copending application.

It will be understood, however, that the instant disclosure is merely illustrative and not limitative of the invention which is as defined in the appended claims.

Referring to the accompanying drawings:

Figure 1 is a front view of a radio transmitter hereinafter termed a pull-box, embodying the 50 invention;

Figure 2 is a front view of the auxiliary door of the pull-box shown in Figure 1, said auxiliary door being open to show the release lever mounted on the main door of the box;

2

Figure 3 is a partial view of the inside of the main door of the box shown in Figure 1, showing the inner end of the release lever;

Figure 4 is a view of the interior of the box, Figure 1, the main door being open;

Figure 5 is a top view of the motor driven timer mechanism used in the box, Figure 1, with the driving spring omitted;

Figure 6 is a diagrammatic side view of the 10 mechanism shown in Figure 5, with the driving spring and its shaft and gear omitted; and

Figure 7 is a circuit diagram of the radio transmitter shown in Figure 1.

Referring to Figure 1, the numeral 10 denotes 15 the usual fire alarm box containing all of the apparatus hereinafter described.

The box has a main door 11 which is provided with a lock 12 so that after the pulsing dial is preset as hereinafter described after each use, 20 the door is locked by the fireman so that the public cannot gain access to the interior of the box.

The main door 11 is provided with an auxiliary door 13 which is hinged at the bottom at 14 and provided with a spring 15 which urges the door to closed position, so that normally the outer end of the release lever 16 to be presently described is protected from the elements.

The release lever has a frame 17 which is secured within the main door, the inner surface 30 of which is shown at 18, Figure 3, and the ears 19 of the release lever firmly support the inner portion 20 of the release lever. A spring 21 is positioned between the release lever and its support so that the outer end of the release lever 35 is always held up in the position shown in Figure 2. The release lever carries a laterally extending pin 22 adapted to engage and trip the power driven timer unit to be presently described.

Inside the box 10 is mounted a panel 23 behind which is mounted, in any suitable manner, the oscillator, amplifier and modulator for the transmitter, connected as shown in Figure 7. These may be of any desired type and, as their construction is well known, they will not be herein described in detail.

Also mounted on this panel 23 is a motor driven timer unit 24, a gong 25 and the pulsing means 26. The latter can be an ordinary telephone dial such as commonly employed in automatic telephone systems.

The space 27 in the box may be utilized for the batteries or other power supply for the transmitter. The timer mechanism 24 may be motor

driven and any suitable form of motor may be used, such as an electric motor or spring motor.

If an electric motor is used, a suitable switch, not shown, starts the motor when the release lever 16 is operated. For the sake of simplicity, however, the motor will be described as a spring motor and the spring is omitted from the drawings, it being sufficient to state that the spring is wound up by means of the key 28 on its shaft in the usual way, the fixed end of the spring being secured to an anchor pin on a fixed part of the casing in the usual manner.

The first driving wheel in the gear train shown in Figure 5 is indicated at 29 and drives a pinion 30 mounted on a shaft 31 carrying cams 32, 33 and a gear 34 meshed with the pinion 35 on shaft 36 carrying the escape wheel 37.

The escape wheel 37 engages the teeth of the double pawl 38 which has a bifurcated end at 39 engaging the strike lever 40, carrying the usual ball 41 adapted to strike the gong 25 positioned adjacent thereto.

It will be observed that the parts so far described constitute a spring motor which may be of any desired construction and which will, when released, operate at a speed determined by the escapement 37, 38.

The cam 32 carries a pin 43 adapted to engage the notch 42 in the upper end of the lever 44 pivoted at 45, and having a laterally extending arm 46 carrying an outwardly extending pin 47 adapted to be engaged by the pin 22 of the release lever.

Obviously, as long as the pin 43 is in the notch in lever 44, the device will not operate, but as soon as the pin 47 is raised upwardly by pulling down on the release lever 16, pin 43 moves out of the slot in the arm 44 and the cam 31 is revolved in the direction of the arrow thereon and will make one revolution.

The arm 44 is urged to the left by means of spring 48 and lies in the path of revolution of pin 43, which strikes the slanting nose of the lever 44 and drops into the slot therein, stopping the operation of the device after one complete revolution of the cams.

It will be seen that as soon as the device is released to operation, the cam 33 releases a switch 49, thereby closing the power circuit to the oscillator, amplifier and modulator of the transmitter, which remains closed during one revolution of said cam, until the parts assume the relative position shown in Figure 6, whereupon the circuit through switch 49 is again opened and remains open while the device is not in operation.

About four seconds after the operation of switch 49, cam 32 engages the roller 50 on the lever 51 which operates the pawl 52, withdrawing same from the slot 53 in the edge of the dial 26, which has been pre-set to the desired number. This releases the dial and the contacts therein pulse the oscillator of the transmitter in a known manner, and the transmitter accordingly broadcasts the desired number.

During the entire operation just described, the gong 25 is being struck so that the person sending in the alarm will know that the mechanism is in operation. The spring has sufficient energy to operate the device about 20 times without any appreciable slowdown and it will be observed that, even should the device slow down, the operation of the timer mechanism 24 is not affected, as this is accomplished by the wound-up spring in the dial 26 which is pre-set after each operation.

It will be observed that the notch 53 in the

edge of the dial 26 is opposite the digit corresponding to the pulses that the pull-box is to transmit, and that to re-set the dial, it is merely necessary to revolve same in a clockwise direction to the limit of its travel and then release it, whereupon the pawl 52 will fall into said notch, said pawl being urged upwards in any suitable manner such as by means of the spring 54.

From the foregoing, it will be evident that in order to send in an alarm, it is only necessary to pull down the auxiliary door 13, pull down the release lever 16, thereby starting the operation of the unit 24 which first will close switch 49 to supply current to the transmitter tubes and then, after said tubes are in operating condition, the unit will release the dial 26 to send in the proper signal.

Upon arrival at the box, the fireman will unlock same and re-set the dial 26 and if necessary, re-wind the unit by means of the key 28.

It will be observed that the unit 24 needs only two wires for its operation, namely, those going to the switch 49, and that same may be removed for inspection and repair and replaced without disturbing the connections to the dial 26 or any of the transmitter connections.

What is claimed is:

1. A radio transmitter comprising an oscillator, amplifier and modulator and a source of current all interconnected to produce an audio modulated carrier wave to be broadcast; a casing for said transmitter having a main door; a release lever mounted on said door and extending outwardly therefrom and into said casing; an auxiliary door mounted on said main door and enclosing the outer end of said lever; power-driven means within said casing including a switch for controlling the application of said source of current to said oscillator, amplifier and modulator, said means being mechanically interconnected to said lever for release thereby; means connected to said power-driven means adapted upon operation thereof to pulse said carrier wave including a manually settable dial adapted to be preset and so held; and means controlled by said power-driven means for holding said dial in said preset position until released by the operation of said power-driven means.

2. In a radio transmitter, a motor driven timer, a control mechanism adapted to lock said timer against operation, a manually operable release lever, means controlled by said lever to mechanically release said timer to cause said control mechanism to make a single revolution and return to locked position, a switch for controlling the operation of said transmitter operatively controlled by said mechanism and manually resettable pulsing means controlled by said mechanism.

3. In combination, a box-like casing having a door; a panel mounted within said casing; a radio transmitter mounted on said panel; a release lever mounted on said door and extending into said casing; a spring extending between said door and said lever and tending to hold said lever in a non-operating position; a power-driven device mounted on said panel and adapted to be mechanically engaged and released for operation by said lever; a power supply; a switch operated by said power-driven device for connecting said power supply to said transmitter; a spring operated pulsing device on said panel and connected to said transmitter; and means operated by said power-driven device for releasing said pulsing device to pulse said transmitter; said pulsing device comprising a rotary dial having

a notch therein, and said power driven devices including a pawl normally engaging said notch to hold said dial ready for operation upon the withdrawal of said pawl by the operation of said power driven device.

4. In combination with a radio transmitter, a power driven device adapted for cyclic operation, mechanical means adapted to lock said device against operation, a manually operable release lever adapted when moved to mechanically release said means to permit said device to operate, a switch adapted to be closed by said device to connect a source of operating current to said transmitter for a predetermined period of time and then disconnect the same, a spring operated pulsing device for pulsing said transmitter cyclically controlled by said power driven device and adapted to pulse said transmitter for at least a portion of the time said switch is closed, and means for manually setting said pulsing device to deliver a predetermined number of pulses at each operation.

5. In a device of the character described, a radio transmitter, a circuit connected to said transmitter including a source of current for the operation thereof, a normally open switch in said circuit, a manually settable spring operated

pulsing device connected to said transmitter adapted when released by the operation of its spring to pulse said transmitter, a power driven cyclic timer adapted to sequentially operate said switch and pulsing device, and manually operable means for starting said timer.

6. The device as claimed in claim 5 wherein all said parts are enclosed within a casing and said manually operable means extends through a wall thereof.
